No. 36,859.

Patented March 29, 1904.

UNITED STATES PATENT OFFICE.

SETH H. LEAVENWORTH, OF CINCINNATI, OHIO, ASSIGNOR TO THE HOMAN SILVER PLATE COMPANY, OF CINCINNATI, OHIO, A CORPORATION.

DESIGN FOR A MOUNTING FOR METAL DISHES.

SPECIFICATION forming part of Design No. 36,859, dated March 29, 1904.

Application filed February 10, 1904. Serial No. 193,016. Term of patent 3½ years.

To all whom it may concern:

Be it known that I, SETH H. LEAVENWORTH, a citizen of the United States, residing at 910 Summit avenue, Cincinnati, in the county of Hamilton and State of Ohio, have invented a new, original, and ornamental Design for Mountings for Metal Dishes.

The figure of the drawing shows the design for the mounting of the metal dishes in plan.

What I claim as new, and desire to secure to by Letters Patent, is—

The ornamental design for a mounting for metal dishes, as shown.

SETH H. LEAVENWORTH.
